UNITED STATES PATENT OFFICE.

EDGAR D. MEADE, OF OLEAN, AND HERBERT F. YOUNGLOVE, OF BUFFALO, NEW YORK.

DEVICE FOR CONVERTING MOTION.

1,265,936.

Specification of Letters Patent.

Patented May 14, 1918.

Application filed June 5, 1917. Serial No. 172,982.

To all whom it may concern:

Be it known that we, EDGAR D. MEADE and HERBERT F. YOUNGLOVE, citizens of the United States, residing at Olean and Buffalo, respectively, in the counties of Cattaraugus and Erie, respectively, and State of New York, have invented certain new and useful Improvements in Devices for Converting Motion, of which the following is a specification.

This invention relates to improvements in devices for transmitting motion, and has for one of its objects to provide a device wherein the parts are adjustable to take up lost motion and in which the parts are interchangeable and readily detachable so that broken or impaired parts may be restored without discarding the other parts.

With these and other objects in view, the invention consists in certain novel features of construction, as hereinafter shown and described and then specifically pointed out in the claims; and in the drawings illustrative of the preferred embodiment of the invention—

Figure 1 is a front elevation of the improved device;

Fig. 2 is a section on the line 2—2 of Fig. 1;

Fig. 3 is a section on the line 3—3 of Fig. 1;

Fig. 4 is a section of the shell on the line 2—2 of Fig. 1 without the movable parts;

Fig. 5 is a rear elevation illustrating a modification in the construction;

Fig. 6 is a section on the line 6—6 of Fig. 5;

Fig. 7 represents perspective views of one set of the guide devices, with the parts separated;

Fig. 8 represents a portion of the connecting rod and its head together with the wrist pin, adjusting members separated and in perspective;

Fig. 9 is a detached perspective view of one of the slidable blocks.

Corresponding and like parts are referred to in the following description and indicated in all the views of the drawings by the same reference characters.

The improved device may be applied to various forms of machinery to which rotary motion is to be transmitted, and it is not desired to limit the invention to any specific form of machinery or apparatus, but for the purpose of illustration the improved device

is shown arranged to rotate a shaft represented conventionally at 10, and suitably supported by a bearing 11, the latter supported upon a suitable standard, or other support, not shown.

The improved device comprises a shell-like structure including a rear disk-like portion 12 having an annular rim 13 secured thereto by any suitable means, for instance by screws, or like fastening devices as shown in Figs. 1, 2, 3 and 4, or by set bolts 47 as shown in Figs. 5 and 6. The member 12 is provided with a relatively long hub 14 in which the shaft 10 is supported, and secured to rotate therewith by set screws 14', the hub providing the requisite length of bearing for the shell and its attachments.

Supported within the shell 12—13 are triangular supporting members, one of which is shown in perspective in Fig. 6. The supporting members are precisely alike and are interchangeable within the shell.

Each of the supporting members is indicated as a whole by the character 15, and each provided with a projection 16 extending from the outer edge and the remaining edges beveled, as shown at 17. The supporting members 15 are so arranged that when disposed within the shell their confronting edges are spaced apart to form guideways 18, the beveled edges 17 of the members 15 forming the sides of the guideways.

Four of the members 15 are employed so that the guideways radiate from a common center, as shown in Fig. 1. Each of the members 15 is provided with guide-slots 19 which engage over ribs, indicated at 20, which project from the inner face of the portion 12 of the shell. The guide-slots 19 and the ribs 20 extend in parallel relation to each other and at right angles to the outer faces of the members 15, so that the latter are movable toward and away from the center of the shell and of the shaft 10 and thus control the width of the guideways 18, as hereinafter explained.

Clamp bolts 23 extend through the members 15 and the portion 12 of the shell, and are formed with countersunk heads engaging in countersunk apertures in the members 15 and provided with clamp nuts 24 bearing against the inner face of the member 12. The member 12 is formed with slots indicated at 25 where the bolts 23 pass through, so that the members 15 may be adjusted toward and away from the center of

the shaft to any required extent within the range of the slots 25, and thus hold the members 15 in their adjusted position.

Fitting within the spaces between the members 15 and the rim at each side of the projection 16, are adjusting blocks 26, the inner faces of the blocks bearing flatly against the outer edges of the members 15 and the outer faces of the blocks curved to correspond to the curvature of the inner face of the rim 13. Operating through each of the projections 16 is a clamp bolt 27 upon which adjusting nuts 28 are mounted and operate to adjust the blocks 26 toward and away from the projections 16 to cause their outer curved faces to bear against the inner face of the rim 13. By this arrangement it will be obvious that the members 15 may be adjusted toward and away from the center 20 of the shaft 10 and thus control the width of the guideways 18, and the blocks 26 may be likewise adjusted to hold the members 15 firmly in their adjusted position. The bolts 23 and 27 enable these adjustments to be made, and coöperate to firmly lock the members 15 in their adjusted position.

Movably disposed in the guideways 18 are coacting sliding members 29 which are formed, as shown in Fig. 8 with beveled sides conforming to and closely engaging the beveled edges of the members 15. Each of the slides is provided with a wrist pin 30. Two of the members 29 are employed and are of greater length than the width of the guideways 18, so that the slides will move past the inner terminals of the guideways and not be deflected from their paths. A connecting rod comprising a stock portion 31 and a head portion 32 forms a part of the improved device, the head portion being of sufficient length to engage both of the wrist pins 30, as shown in Fig. 1. The head portion 32 of the connecting rod is formed with transverse openings or guideways 33 for the bearing blocks or "brasses" which engage the wrist pins, the guideways being separated by a web 34. Each pair of the bearing blocks or brasses which engage in the guideways 33 are precisely alike and the description of one set or pair will suffice for both. The bearing blocks or brasses for each of the openings 33 are shown in perspective in the lower portion of the group of members represented in Fig. 7. One of the bearing blocks 55 is represented at 35 and fits flatly against the outer end of one of the guideways 33 and against the flat inner end of the other guideway 33. The other bearing block or "brass" represented at 36, fits within the 60 guideway 33 at the opposite sides of the wrist pins from the member 35 and are formed with V shaped portions 37, the V shaped portions of the two blocks extending toward each other, as shown in Fig. 1. The head member 32 of the connecting rod is

provided with other guideways 38 extending through their upper and lower edges and communicating with the guideways 33. The guideways 38 are designed to receive key blocks 39; each block having one side at right angles to the longitudinal axis of the connecting rod, while the other edge 40 is beveled to correspond to and bear against the inclined portions 37 of the member 36. The blocks 39 are arranged in opposite relation, 75 or with one set operating through the top of the head 32 and the other set operating through the bottom of the head, as shown in Fig. 1. The key members 39 are apertured to receive clamp bolts 41 provided with 80 clamp nuts 42 whereby the key blocks may be moved toward each other and thus apply pressure to the members 36. By this means the "brasses" 35-36 may be adjusted to control the position of the connecting rod 85 relative to the wrist pins, and take up lost motion which may occur, and maintain the parts in adjusted position. The bolts 41 are preferably provided with jam nuts 43 to prevent the clamp nuts 42 from working loose. 90

By this arrangement when reciprocal motion is imparted by any suitable means to the connecting rod 31 rotary motion will be imparted to the shell member 12-13, and a universal adjustment between the parts 95 secured by simply manipulating the holding nuts 28 and 42. The improved device may be applied without structural change for driving wheels or devices of various sizes and forms and thus adapt the device 100 to various forms of machinery and to machinery employed for various purposes.

In Figs. 5 and 6 a modification of the construction is shown consisting in an attachment whereby power may be transmitted from the rim of the member 12 instead of from the shaft 10. The modified attachment consists in providing the rim 13 with an annular gear rack 48 and an inwardly directed flange 49, the latter bearing 110 against the rear outer face of the member 12 and secured thereto by set bolts or like devices 47. The flange 49 is provided with inwardly directed projections 50, while the remainder of the flange extends outwardly 115 of the bolts 23 and the nuts 24, so that the presence of the flange and its projections do not interfere with the operation of the bolts whereby the members 15 are secured 120 in position.

Having thus described the invention, what is claimed as new is:

1. A device of the class described comprising a body mounted for rotation and including a laterally directed rim, a plurality of members movably supported on said body with their confronting edges in spaced relation to form guideways crossing each other in angular relation, coacting angular members disposed between said sup- 130

porting members and the rim of the rotative body, means for adjusting said angular members toward and away from each other to effect the adjustment of the supporting members, sliding members movable in said guideways, and an operating member pivotally coupled to said sliding members.

2. A device of the class described comprising a body mounted for rotation and including a laterally directed rim, a plurality of members movably supported on said body with their confronting edges in spaced relation to form guideways crossing each other in angular relation and each provided with an outwardly directed projection, coacting angular members disposed between said supporting members and the rim of the rotative body, adjusting devices carried by the projections of said supporting members and operating to move the angular members toward and away from each other to effect the adjustment of the supporting members, sliding members movable in said guideways, and an operating member pivotally coupled to said sliding members.

3. A device of the class described comprising a body mounted for rotation and including a laterally directed annular rim, a plurality of members movably supported on said body with their confronting edges

in spaced relation to form guideways crossing each other in angular relation, coacting members disposed between said supporting members and the rim of the rotative body, one face of each coacting member being curved to correspond to and engage the inner face of the annular rim and with another face corresponding to and bearing against the outer face of the adjacent movable member, and means for adjusting said coacting members toward and away from each other to effect the adjustment of the supporting members.

4. A device of the class described comprising a rotative body, a laterally directed rim attached to said body and extending laterally thereof, a plurality of members movably supported on said body with their confronting edges in spaced relation to form guideways crossing each other at right angles, means operating between said rim and the movable members for adjusting the same radially of the body, sliding members movable in said guideways, and an operating member pivotally coupled to said sliding members.

In testimony whereof we affix our signatures.
